[57] CLAIM

The ornamental design for a stair carpet tool handle, as shown and described.

DESCRIPTION

FIG. 1 is a perspective view of a stair carpet tool handle showing my new design;

FIG. 2 is a top plan view thereof;

FIG. 3 is a right side elevation view thereof, the left side elevation view being identical;

FIG. 4 is a rear elevation view thereof; and,

FIG. 5 is a front elevation view thereof.

The broken line showing of a tool blade in FIGS. 1-3 for illustrative purposes only and forms no part of the claimed design.
